MULTIPLE-SWITCH STARTER.

No. 918,609.

Specification of Letters Patent.

Patented April 20, 1909.

Application filed May 20, 1907, Serial No. 374,706. Renewed January 11, 1909. Serial No. 471,777.

To all whom it may concern:

Be it known that I, LEWIS L. TATUM, a citizen of the United States, residing at Norwood, in the county of Hamilton and State 5 of Ohio, have invented new and useful Improvements in Multiple-Switch Starters, of which the following is a full, clear, concise, and exact description, reference being had to the accompanying drawing, forming a part 10 of this specification.

My invention relates to improvements in motor controllers.

It is particularly applicable to controllers in which a plurality of hand operated 15 switches are used for controlling the resistance.

According to the preferred form of my invention, I provide a plurality of hand operated switches which are preferably adapted 20 to be closed in a definite sequence to remove the starting resistance from the motor circuit, and one of which is adapted to control the motor circuit. These switches are maintained in their closed position, preferably by 25 a low voltage device. This device acts upon failure of voltage or upon the drop of voltage below a predetermined point to cause said switch which controls the motor circuit to open. It is desirable in event the starting 30 resistance is left in circuit for longer than a predetermined period that the circuit be opened. The resistance of motor starting devices is usually made of wire which while it is of sufficient capacity to carry the current for a short period, during the starting 35 of the motor, is not of sufficient capacity to carry the current for a long period of time. In the present invention I prevent the leaving of the starting resistance in circuit for 40 longer than a predetermined period of time by the provision of a plurality of switching devices which control the low voltage retaining device. These switching devices in their 45 operative position tend to either open the circuit through the low voltage device, or close a short circuit around the device, whereby the same is caused to release the motor circuit switch and open the motor circuit. I 50 preferably provide one switching device for each of the hand operated switches except the last and when each hand operated switch is moved to a closed position it moves its cor-

responding switching device to an inoperative position, but immediately releases the same to permit it to move toward operative 55 position, to close a short circuit around the low voltage device. However, before the switching device reaches its operative position, the next hand operated switch is closed which moves another of the switching devices to inoperative position again opening 60 the short circuit. In this manner each hand operated switch is moved closed before the preceding switching device moves to operative position. If the hand operated switches 65 are not thus closed, the switching devices will cause the low voltage device to release the switches closed and open the circuit. The last hand operated switch to be closed, is 70 provided with a switch which when the hand switch is closed, renders the switching devices inoperative. In this manner I am enabled to provide means which opens the circuit in event the starting resistance is left in circuit for a longer than a predetermined 75 time.

For the purpose of disclosing my invention, I have illustrated in the accompanying drawings one embodiment thereof.

In said drawings Figure 1 is a front elevation of the starting device of my invention, Fig. 2 is a section on the line 2--2 of Fig. 1, Fig. 3 is a similar view with the switches open, Fig. 4 is a detailed view of the latch mechanism for holding the switches in a 80 closed position, Fig. 5 is a sectional top view of one of the switches and a top view of the coöperating rocking dogs, Fig. 6 is a detail of one of the rocking dogs employed, Fig. 7 is a perspective view of one end of one of the rods 85 carrying a switching device. Fig. 8 is a detail perspective view of the catch for operating the switching device, and Fig. 9 is a diagrammatic view of the circuit connections.

According to the embodiment of my invention illustrated, the switches 1, 1^a, 1^b, 1^c, and 1^d, are suitably pivoted or journaled at one end and are provided at the opposite end with suitable operating handles. I have shown the several switches as journaled upon 95 a shaft or rod 2, mounted in bearings 3, formed on brackets 4. The bracket 4 also supports a rod 5, which is threaded through a rubber tube 6, which serves as a cushion or 100

buffer against which the extended ends of the switches are adapted to impinge when thrown open. Each of the switches carries a contact device 7 made preferably in the form 5 of a number of strips of copper laid face to face, the free ends being adapted to engage contact surfaces to complete the circuit. Upon the base board 8, which carries the various operating parts of the controlling device, and which is preferably formed of slate, soapstone, or like material, is mounted a contact bar 9, with which one end of the contact device 7 of each switch is adapted to engage, the other end of said device being adapted to 10 engage one of the contact terminals 10, 10^a, 10^b, 10^c, and 10^d. The contact devices 7 of the switches 1 and 1^d are preferably made wider than the remaining contact devices as these devices are adapted to carry heavier 15 current than the remaining devices. Upon the terminal 10 is provided a binding post 11 by which suitable electrical connection may be made therewith, and a like binding post 12 is carried by the contact 10^d. Upon the 20 terminal 10 is mounted a carbon block 13, and a similar carbon block 14 is mounted on the end of the contact bar 9. The first switch has mounted thereon laterally extending spring arms 15 and 16, supporting on 25 the ends thereof, carbon blocks 17 and 18. When the switch is moved to close the circuit, the block 13 engages the block 17, and the block 14 engages the block 18, thereby closing the circuit from the terminal 10, to 30 the terminal 9. The further movement from the switch 1 causes contact devices to close together the terminals 10 and 9. Likewise, when the switch 1 is moved outward, the contact devices 7 leaves the terminals 9 and 35 10, before the carbon blocks separate so that any arc which may be formed by the opening of the circuit will take place between the carbon blocks instead of between the metallic surfaces. 40

45 Near the upper end of the switch 1, a lug 19 is formed which carries a laterally extending projection 20, which may take the form of a screw. Mounted upon the base board 8, above the arm 1 is a retaining magnet 21, having an armature 22 pivoted at 23, and having a laterally and upwardly extending lug 24. When the arm 1 is moved to close the circuit, the projection 20 engages the side of the armature 22 to move the same against 50 the magnet pole, and the magnetism of the magnet 21 retains the armature 22 in this position. The swinging of the armature 22 carries the lug 24 upon the exterior of the projection 20, so that said projection will 55 rest in the slot formed between the lug 24 and the face of the armature 22. So long as the magnet 21 remains energized, the arm 60 will thus be held in a closed position. When, however, the magnet 21 is deenergized, the 65 armature 22 will be released and the weight

of the arm 1 will carry the same to the position shown in Fig. 3, thereby rocking the armature 22 upon its pivot as shown.

Mounted upon a rod or shaft 25, pivoted in suitable bearings upon the base plate 8, are 70 rocking dogs 26, 26^a, 26^b, 26^c. Each dog has its rear end so shaped as to engage the base plate and limit the downward movement of the dog when free. Upon the end of the dog, to the right hand side, an upwardly extending lip 27 is provided, which has its front edge curved and its rear edge perpendicular to the upper surface of the dog. The under side of the dog has a lip 28 which extends throughout its entire length, and is rounded off at 80 the left hand edge. The switches 1^a to 1^d, inclusive, are each provided with a latch 29, pivoted to the arm at 30, in a slot 31, the walls of which slot limit the movement of the latch relatively to the arm. The first switch 1 has no latch. Below the latch and formed integrally with the switch is a lug 32, projecting toward the base plate and consisting of two parts 33 and 34. The part 33 is squared in section and flat upon the end, and 90 when the switch is in a position to close the circuit presents a vertical surface. The upper part of the part 34 is inclined or chamfered at an acute angle.

Mounted below the switches 1 to 1^c are a 95 plurality of switching devices, 35^a, 35^b, 35^c, and 35^d, one for each of the switches 1 to 1^c. Each of the switches 35^a to 35^d is mounted upon a vertically movable arm 36, the lower end of which is provided with a plunger 37 operating in a dash-pot 38, and the upper end of which is provided with a small cross arm or catch 39. The dash-pot 38 is mounted upon suitable brackets 40, which is bolted or otherwise secured to the base plate 8, and which is provided with a projection 41, forming a guide for the upper end of the rod 36. The rod 36 is provided with a flattened surface 42 which accommodates a projection 43, formed in a guide stud 41, and which projection, engaging the walls of the slot 42, limits the movement of the rod 36. The lower projecting end of each of the switches 1 to 1^c carries a pivoted bell crank lever 44, pivoted at 45, and having one arm thereof bifurcated as at 46 between which bifurcations the vertically movable arm 36 is adapted to fit. When the switch is in its open position the bifurcated portions 46 are beneath the catch 39 of the rod, and as the arm is moved to its closed position and the bell crank arm 44 is moved upwardly, carrying with it the rod 36 and raising the switching device carried thereby, until the bifurcations 46 are moved out of engagement with the catch 39 by the moving of the switch arm to its final closed position. The moving of the bifurcations 46 out of engagement with the catch 39 permits the vertically movable rod to drop and with it the switching device car- 110 115 120 125 130

ried thereby. The dash-pot 38 is constructed to retard the downward movement of the rod, thereby retarding the downward movement of the switching device. The switching devices 36^a to 36^d are arranged to bridge pairs of contacts 47^a and 47^b, 48^a and 48^b, 49^a and 49^b, and 50^a and 50^b, respectively. The last switch arm 1^d has no corresponding switching device, but carries a spring switch arm 51, which is adapted to engage when the switch arm is open, a stationary contact 52 mounted upon the base 8.

I have diagrammatically illustrated in Fig. 9 the circuit connection for the device above described. Referring now to Fig. 9, the contact terminal 10 is connected with the positive side 53 of the supply mains. The contact terminal 10^d is connected by the conductor 54 with one terminal of the armature 55 of the motor. The opposite terminal of the armature is connected by conductor 56 with the negative side 57 of the supply mains. The contact bar 9 is connected by conductor 58 with one terminal of the magnet 21, and by the conductors 59 and 60, with one terminal of the field winding 60 of the motor, the opposite terminal of said field winding being connected with conductor 56. The opposite terminal of the magnet 21 is connected through the high resistance 61, with the negative side 57 of the line, and by a conductor 62, with the contact 47^a of the first switching device 35. The adjacent contacts of the remaining switching devices 35^a, 35^b, 35^c are connected together and the contact 50^b is connected to the stationary contact 52. One section of resistance 63 is connected between the contact bar 9 and the contact terminal 10^a. A resistance 64 is connected between the contact terminals 10^a and 10^d and is divided into sections which are connected with the contacts 10^b and 10^c.

The operation of the device above described is as follows: Assuming that it is desired to start the motor, the switch 1 is closed to first close the circuit between the carbon blocks and finally to close together the terminals 9 and 10 directly through the contact device 7. The armature 22 is engaged and moved against the pole of the retaining magnet 21, and, as the retaining magnet is energized, it serves to maintain the switch arm in the closed position. At the same time that the switch 1 is moved to its closed position, the bifurcations 46 of the lever 44, carried by the switch engage the projection 39 of the vertical rod 36 opposite said switch, and raise said rod carrying with it the switching device 35^a, and breaking the circuit at the contacts 47^a and 47^b. Circuit is now established from the positive side 53 to the contact 10, across the arm 1 to contact 9, thence by conductor 58, through the winding of the magnet 21, and through the high resistance

61, to the negative side 57 of the line. The magnet 21 is thus energized and holds the arm 1 in its closed position. Circuit is also established from the positive side 53 of the line to contact 10, across the arm 1, contact 9, through the resistance 63 and 64, to contact 10^d, thence by conductor 54, through the armature 55 of the motor, and by conductor 56 to the negative side 57 of the line. The circuit is also established from the conductor 58, by conductor 59, through the field winding 60 of the motor, to conductor 56. The motor is thus started with all of the resistance in circuit. When the switch 1 is moved to its closed position, the bifurcations 46 of the bell crank arm 44 disengage from the catch 39, permitting the rod 36 of the switching device 35 and the switch to move downwardly. This downward movement, however, is retarded by the dash-pot 38. In moving the switch to the closed position, the oblique wall 34 of the lug 32 thereof engages the under face of the first rocking dog 26 and raises the same into the position shown in full lines in Fig. 4. Before the switch 35 moves into engagement with its contacts 47^a and 47^b, the second switch arm is closed and as the dog 26 is in its raised position, the latch 29 of the switch 1^a will ride over the lip 27 of the dog 26 and engage the vertical wall 34 thereof, thereby holding the switch 1^a in its closed position. The closing of the switch 1^a causes the bifurcations 46 of the arm 44 carried thereby to engage the vertical rod 36 of the switch 35^b and raise the rod as has been previously described, with respect to the switch 35^a. When the switch is finally closed, the catch 46 disengages from the catch 39, permitting the rod and with it the switch 35^a to again move to its closed position. In closing the switch arm 1^a, the oblique wall 34 of the lug 32 thereof engages the next rocking dog 26^a, raising the same in a position to be engaged by the latch 29 of the switch arm 1^b, and in a similar manner each of the succeeding switch arms is closed. Also the closing of each switch arm raises its corresponding switching device. It is necessary that each succeeding switch arm be moved to its closed position before the switching device of the preceding switch arm moves to its closed position. Otherwise the switching device will drop and establish a short-circuit from the positive side 53 of the line to contact 10, thence across the arm 1, through the shaft or rod 2, to the switch 1^a, thence to the switch 51, thence to stationary contact 52, across the switches 35^d to 35^a, by conductor 62, through the high resistance 61, to the negative side of the supply main. This short-circuits the magnet 21 and de-energizes the same, permitting the switches closed to open. If, however, each of the switches 1 to 1^d are closed before the switching devices 35^a to 35^d are permitted to close, 130

the short-circuit will be always open, and the magnet will remain energized. When the last switch is closed, the switch member 52 is moved off of the stationary contact, thereby 5 opening the short-circuit around the magnet 21, and the magnet remains energized to hold all of the switches in a closed position. It will thus be seen that by the provision of the switching devices 35^a to 35^d, I am enabled to 10 place a time limit upon the closing of each switch, thereby avoiding the heating of the resistance unduly.

If it is desired to cut in the resistance and open the circuit through the motor, the retaining magnet 21 may be deenergized in any suitable manner, and the switch 1 will be released and fly outward to the position shown in Fig. 3. In moving outward, the first 15 rocking dog 26 is permitted to fall, and the latch 29 of the second switch 1^a is thus released, and said switch likewise flies out. The second switch 1^a permits the second rocking dog 26^a to fall, thereby releasing the third switch. In a similar manner each 20 switch releases the next succeeding switch, until all of the switches have been released.

Any attempt to close one of the switches out of its regular order is prevented, due to the fact that the flat face 33 will engage the 30 end of the rocking dog when the dog is in its lowermost position, and it is only when the dog has been raised to its upper position that the flat face 33 will be permitted to pass beneath the end of the rocking dog. Moreover, unless the rocking dog is in the upper 35 position, the latch 29 will not engage the lip 27 upon the dog, and the rocking dog will be held in the upper position only when the immediately preceding switch has been closed. 40 The accidental or intentional closing of one of the switches out of its regular order is thus effectually prevented.

It is obvious that various changes and modifications may be made in the construction and arrangement of my device as varying the electric circuit, modifying the retaining device and the like, without departing from the spirit of my invention as set forth in the appended claims.

50 Having thus described my invention what I claim as new and desire to secure by Letters Patent is:

1. The combination with a plurality of switches adapted to be closed in a definite 55 sequence, of a plurality of means for causing the circuit to be opened through the switches closed when the next succeeding switch remains unclosed for a time longer than a predetermined period.

60 2. The combination with a plurality of switches, of a plurality of means set by said switches for causing the switches to open when a part of the switches remain unclosed for a longer time than a predetermined 65 period.

3. The combination with a plurality of switches, of a retaining magnet for holding the same, and a plurality of means successively set by said switches for causing said retaining magnet to permit the switches to 70 open when part of the switches remain open for a predetermined time.

4. The combination with a plurality of switches, of retaining means therefor, a plurality of devices tending to move to render 75 said retaining means inoperative after each switch is closed, one of said devices being adapted to be set upon the closing of each switch.

5. The combination with a plurality of 80 switches, of a retaining device for holding the same closed, and a plurality of devices one operated by each switch for controlling said retaining device.

6. The combination with a plurality of 85 switches, of a retaining means for holding the switches closed, and a plurality of devices one controlled by each switch for operating said retaining means to open the switches unless each switch is closed within 90 a predetermined time after its preceding one.

7. The combination with a plurality of switches, of retaining means for holding the same closed, a plurality of devices each 95 adapted to release said retaining means within a predetermined period of time after being set, certain of said switches, when actuated, being each adapted to render one of said devices operative, and means whereby the closing of one of said switches will render 100 all of said devices inoperative.

8. The combination with a plurality of switches, of an electroresponsive means for retaining said switches closed, and a plurality of devices each adapted to render said 105 electroresponsive means inoperative at a predetermined time after being set, certain of said switches, when actuated, being each adapted to render one of said devices operative and one of said switches when closed 110 being adapted to render said devices inoperative.

9. In a motor controller the combination with a plurality of switches, of a resistance controlled thereby, a plurality of means, one 115 set by each of said switches, having a tendency to move to a position to cause said switches to open the motor circuit and adapted to open the motor circuit unless all of the resistance is removed from the circuit 120 within a predetermined time.

10. In a motor controller the combination with a resistance, of a plurality of switches for controlling said resistance, a switch among said switches for controlling the motor circuit, a low voltage device cooperating with said switch whereby the same is operated to open the motor circuit in event the voltage falls below a predetermined point, a plurality of switching devices operatively 125 130

connected with said low voltage device and adapted to cause said low voltage device to cause the circuit to be opened unless the resistance is removed from circuit within a 5 predetermined time.

11. In a motor controller the combination with a resistance, of a plurality of switches for controlling said resistance, a switch among said switches controlling the motor 10 circuit, a low voltage device coöperating with said last mentioned switch whereby the same is operated to open the motor circuit in event the voltage falls below a predetermined point, a plurality of switching devices 15 operatively connected with said low voltage device and adapted to cause said low voltage device to cause the circuit to be opened, unless the resistance is removed from the circuit within a predetermined time, and means 20 operated upon the closing of the last switch for rendering such switching device ineffective.

12. In a motor controller the combination with a resistance, of a plurality of switches 25 for controlling the same, a switch among said switches for controlling the motor circuit, a low voltage device coöperating with said switch whereby the same is operated to open the motor circuit in event the voltage falls 30 below a predetermined point, a plurality of switching devices operatively connected with said low voltage device and adapted to cause said low voltage device to cause the circuit to be opened, mechanical connection 35 between said switches and said switching devices, and means operated upon the closing of the last switch for rendering said switching devices ineffective.

13. In a motor controller the combination 40 with a resistance, of a plurality of switches for controlling said resistance, a switch among said switches for controlling the motor circuit, a low voltage device coöperating with said switch whereby the same is operated to open the motor circuit in event the voltage falls below a predetermined point, a plurality of switching devices, one adapted 45 to be set by the closing of each switch except the last, operatively connected with said low voltage device and adapted to cause said low voltage device to cause the circuit to be opened, and means for timing said switching devices.

14. In a motor controller the combination 55 with a resistance, of a plurality of switches for controlling the resistance, a switch among said switches for controlling the motor circuit, a low voltage device coöperating with said switch whereby the same is operated 60 to open the motor circuit in event the voltage falls below a predetermined point, a

plurality of switching devices, one adapted to be set by the closing of each switch except the last, operatively connected with said low voltage device and adapted to cause said low voltage device to cause the circuit to be opened, means for timing said switching devices, and means operated upon the closing of the last switch for rendering said switching devices ineffective. 65

15. In a motor controller the combination with a resistance, of a plurality of switches for controlling the same, a switch among said switches for controlling the motor circuit, a low voltage device coöperating with said 70 switch whereby the same is operated to open the motor circuit in event the voltage falls below a predetermined point, a plurality of switching devices operatively connected with said low voltage device and adapted to cause said low voltage device to cause the circuit to be opened, mechanical connection between said switches and said switching devices, and means for timing said switching devices. 75

16. In a motor controller the combination with a resistance, of a plurality of switches for controlling said resistance, a switch among said switches for controlling the motor circuit, a low voltage device coöperating 80 with said switch whereby the same is operated to open the motor circuit in event the voltage falls below a predetermined point, a plurality of switching devices operatively connected with said low voltage device and 85 adapted to cause said low voltage device to cause the circuit to be opened unless the resistance is removed from circuit within a predetermined time, and means for timing the operation of said switching devices. 90

17. In a motor controller the combination with a resistance, of a plurality of switches for controlling the same, a switch among said switches for controlling the motor circuit, a low voltage device coöperating with said 95 switch whereby the same is operated to open the motor circuit in event the voltage falls below a predetermined point, a plurality of switching devices operatively connected with said low voltage device and adapted to cause 100 said low voltage device to cause the circuit to be opened, unless the resistance is removed from circuit within a predetermined period of time and mechanical connection between 110 said switches and said switching devices. 115

In witness whereof, I have hereunto subscribed my name in the presence of two witnesses.
